UNITED STATES PATENT OFFICE.

JAMES R. MOFFATT AND RALPH S. KELSO, OF CHICAGO, ILLINOIS, ASSIGNEES TO UNION SPECIAL MACHINE COMPANY, OF CHICAGO, ILLINOIS, A CORPORATION OF ILLINOIS.

THREAD-CUTTER FOR SEWING-MACHINES.

1,332,512.

Specification of Letters Patent.

Patented Mar. 2, 1920.

Original application filed December 11, 1916, Serial No. 136,273. Divided and this application filed April 24, 1917. Serial No. 164,095.

To all whom it may concern:

Be it known that we, JAMES R. MOFFATT and RALPH S. KELSO, citizens of the United States, both residing at Chicago, in the 5 county of Cook, State of Illinois, have invented certain new and useful Improvements in Thread-Cutters for Sewing-Machines, of which the following is a description, reference being had to the accompanying drawing and to the figures of reference 10 marked thereon.

The invention relates to new and useful improvements in thread cutting devices for sewing machines, and more particularly to 15 a thread cutting device for cutting the needle thread prior to the removing of the material which is being stitched.

An object of the invention is to provide a thread cutting means which is so disposed 20 relative to the work support and the stitch forming elements as to cut at will one strand of a needle thread loop preparatory to the removal of the material from the machine.

A further object of the invention is to provide 25 a thread cutting device of the above character with means for preventing the operation of the thread cutter except when the needles are in their extreme position away from the work support.

A still further object of the invention is 30 to provide a device for pulling thread from the supply in advance of and preparatory to the thread cutting operation.

These and other objects will in part be 35 obvious and will in part be hereinafter more fully disclosed.

In the drawings, which show by way of 40 illustration one embodiment of the invention:

Figure 1 is a view, partly in side elevation and partly in section, showing a machine having our improved thread cutting mechanism applied thereto;

Fig. 2 is a view, partly in rear elevation 45 and partly in section, of the same;

Fig. 3 is an enlarged view from the front of the machine, showing the thread cutting device and some of the parts of the stitching mechanism;

Fig. 4 is a detail, partly in section, showing the position of the threads and the relation of the thread pull-off thereto;

Fig. 5 is a detail, showing the needles, the

needle threads, and the cutter just as the thread is being severed;

55

Fig. 6 is a similar view, showing the cutter moved away after severing the thread;

Fig. 7 is a detail in side elevation showing the take-up arm and the support for the same.

60

We have shown our invention applied to a sewing machine of the hook needle type and wherein two needles are used. It is obvious that the cutting mechanism may be used in connection with a single needle and 65 only a single needle will be referred to in the general description of the machine.

The needle thread is laid into the hook of the needle after the needle has passed through the material, and the retracting of 70 the needle carries the thread in loop form through the material. The needle then passing up through its own formed loop again engages and forms a loop in the thread which is drawn down through the loop, 75 around the shank of the needle, and thus the stitches are formed. At the end of a stitching operation, when it is desired to remove the material from the machine, our improved thread cutting mechanism is actuated for cutting the thread.

This thread cutter is adapted to engage the loop on the needle, when the needle is 80 fully retracted and holding the thread loop, and cuts only one strand of the needle loop.

85

Prior to the cutting of this strand of the needle loop, however, a pull-off arm is actuated to pull thread from the supply so that, after the thread is cut, the drawing of the material from underneath the presser foot 90 will draw a long length of thread well out from the stitching point so that it will be clamped by the presser foot during the beginning of the next stitching operation. The thread pull-off arm and the cutter are 95 both operated by a knee shift or treadle controlled at the will of the operator, and means is provided which prevents the operation of the thread cutter except when the needle is fully retracted.

100

Referring more in detail to the drawings: We have shown our invention as applied to a machine which is particularly adapted for patching bags. This machine is shown and described in detail and claimed in our 105 copending application, Serial No. 136,273,

filed December 11th, 1916, of which the present application is a division.

The machine is provided with a standard 1 carrying an overhanging arm 2 and a second 5 projecting arm 3 at the outer end of which is mounted a work support 4. The material is held on the work support by a presser foot 5. Reciprocating in suitable bearings is a needle bar 6 carrying, as herein 10 shown, two needles 7 and 8. These needles are of the hook type and are provided with suitable sliding latches for closing the hooks, all of which, together with the mechanism for operating the same, is fully set forth in 15 the application referred to above.

The needle 7 is supplied with a needle thread 7^a and the needle 8 is supplied with a needle thread 8^a. These needle threads pass through suitable tensions, indicated at 1, thence through guide eyes 9—9, respectively, 20 and thence through guiding eyes in a pull-off arm 10. From the pull-off arm 10, the threads are led through a stationary thread guide 11, and thence through thread guides 25 12 and 13 to the movable threading guides 14. These threading guides operate to lay the threads, respectively, in the hooks of the needles when the hooks of said needles are above the material. The needle bar is reciprocated in the usual manner. After the 30 threads have been laid in the hooks of the needles, said hooks moving beneath the material draw the loops down through the material. As the needles again rise, they 35 pass up through the material, engaging the needle threads, and again form loops which are respectively drawn down through the first-named loops, and thus the concatenated stitch loops are formed.

40 Our improved thread cutter is indicated at 15 in the drawings and consists of a blade having a cutting edge 16. The thread cutting blade 15 is carried by a lever 17 which is pivoted at 18 to the bearing bracket on 45 the machine. A link 19 is pivoted at 20 to said lever 17, and the other end of the link is pivoted to an arm 21 by a shaft 22. The 50 shaft 22 on its outer end carries a second arm 23.

55 The take-up arm 10 is pivoted at 24 to a suitable bearing on the overhanging arm. A link 25 is connected to the outer end of this arm at 26. This link at its upper end is pivoted at 27 to a lever 28. The lever 28 is fulcrumed at 29 to the overhanging arm. A rod 30 is connected at 31 to the lever 28, and the other end of this rod is connected through suitable devices either to a knee shift or a treadle so that the rod may 60 be depressed at the will of the operator. A spring 33 normally operates to hold the outer end of the lever 28 depressed and the rod 30 raised. The inner end of the lever 28 carries a depending finger 34. A wheel 65 35 mounted on the outer end of the main

shaft 36 has a hub with a slot 37 formed radially therein. When this slot 37 is in vertical position, as indicated in Fig. 1, the rod 30 may be depressed and the finger 34 will move into the radial slot. When, however, this slot is out of register with the finger, then any attempt to depress the rod 30 will bring the end of the finger against the hub, as indicated in Fig. 2, and prevent the manipulation of the lever 28. 75

The lever 28 carries a pin 38 which extends into a slot 39 in the upper end of a rod 40. The lower end of this rod 40 is pivoted at 41 to the arm 23. When the rod 30 connected with the treadle is raised, the pin 80 38 is adjacent the upper end of the slot 39. This slot affords a lost motion between the lever 28 and the rod 40 so as to permit the lever 28 to have a certain movement before the rod 40 is moved and before the cutter 85 will be operated.

When the machine stops with the needles clear down, the recess 37 will be in line with the finger 34, and the operator may depress the treadle or operate the knee shift, swinging the lever 28 about its fulcrum. The first movement of the needle 28 results in pulling thread from the supply by the swinging of the arm 10. When the pin 38 reaches the end of the slot 39, then the rod 95 40 will be forced downwardly, this will move the shaft 22 in a counterclockwise direction, which will pull on the link 19 and swing the lever 17 so as to cause the cutter to move forward and engage one strand of 100 the loop in the needle thread which is held by the needle. When two needles are used, as shown in the drawings, the edge of the cutting blade is positioned so as to simultaneously engage both needle loops. 105

From the above description, it will be apparent that we have provided a cutter operating mechanism which can only be operated when the needles are retracted and the thread properly positioned for cutting. 110 We have also provided a thread pull-off mechanism which is operated in advance of the actuation of the cutter which severs the threads. Only one strand of the needle thread loop is cut, and this is the strand between the hook of the needle and the material. After this strand is cut, when the material is pulled from the machine the split end of the thread extends through the material and around the hook, and the pulling of the thread out of the machine through the friction of the material on the thread draws the slack pulled off through the thread eyes and the end of the thread well out from underneath the presser foot. When 115 the material is again inserted for the next stitching operation, the end of the thread extends well out from underneath the presser foot and will with certainty be clamped by the edge of the presser foot and 120 125 130

firmlly held so that the thread laying device can lay the thread in the hook of the needle.

It is obvious that minor changes in the details of construction and the arrangements of parts may be made without departing from the spirit of this invention as set forth in the appended claims.

Having thus described the invention, what is claimed as new is:—

- 10 1. The combination of a work support, a hook needle, and devices coöperating therewith for forming chain stitches, a thread cutter, manually operated means for operating the thread cutter to cut one strand only 15 of the thread loop on the needle when the needle is retracted, and means for preventing the operation of said manually operated means except when the needle is retracted and out of the path of the thread cutter.
- 20 2. The combination of a work support, a plurality of hook needles, devices coöperating therewith for independently forming chain stitches with each needle, a thread cutting blade having a cutting edge parallel with a line passing through the needles whereby said cutting blade is adapted to simultaneously engage one strand only of each needle loop and sever the same, and manually controlled means for operating 25 said cutting blade.
3. The combination of a work support, a plurality of hook needles, devices coöperating therewith for independently forming chain stitches with each needle, a thread cutting blade having a cutting edge parallel with a line passing through the needles whereby said cutting blade is adapted to simultaneously engage one strand only of each needle loop and sever the same, manually 35 controlled means for operating said cutting blade, and means for preventing the operation of said manually controlled means except when the needles are fully retracted and out of the path of said cutting blade.
- 40 4. The combination of a work support, a hook needle mounted beneath the work support, a device above the work support coöperating with said hook needle for laying a thread therein, a thread pull-off arm for the 45 needle thread located above the work support, a thread cutting mechanism for cutting the needle thread located beneath the work support, manually operated means for actuating the thread cutter to cut one strand 50 only of the thread loop on the needle when the needle is retracted, said manually controlled means including devices whereby the

thread pull-off arm will be operated to pull off thread in advance of the cutting of the thread loop.

5. The combination of a work support, of a hook needle located beneath the work support and adapted to move through the material to engage the needle thread for forming a loop therein, a thread pull-off located 60 above the work support through which the needle thread passes, a thread cutter located 65 beneath the work support and adapted to cut one strand only of the needle thread loop on the needle when the needle is retracted, and manually controlled means for operating said pull-off and said thread cutter.

6. The combination of a work support, of a hook needle located beneath the work support and adapted to move through the material to engage the needle thread for forming a loop therein, a thread pull-off located 70 above the work support through which the needle thread passes, a thread cutter located 75 beneath the work support and adapted to cut one strand only of the needle thread loop on the needle when the needle is retracted, and manually controlled means for operating said pull-off and said thread cutter, 80 said manually controlled means including devices whereby the thread pull-off is 85 operated in advance of the thread cutter.

7. The combination of a work support, of a hook needle located beneath the work support and adapted to move through the material to engage the needle thread for forming a loop therein, a thread pull-off located 90 above the work support through which the needle thread passes, a thread cutter located 95 beneath the work support and adapted to cut one strand only of the needle thread loop on the needle when the needle is retracted, manually controlled means for operating said pull-off and said thread cutter, 100 said manually controlled means including devices whereby the thread pull-off is 105 operated in advance of the thread cutter, and means for preventing the operation of the manually controlled means except when the needle is fully retracted and out of the path of the cutter.

In testimony whereof, we affix our signatures, in the presence of two witnesses.

JAMES R. MOFFATT.
RALPH S. KELSO.
